UNITED STATES PATENT OFFICE

102,170

DESIGN FOR TILE

Eugene Parker, Los Angeles, Calif.

Application January 13, 1936, Serial No. 60,546

Term of patent 3½ years

To all whom it may concern:

Be it known that I, Eugene Parker, a citizen of the United States, residing at 1525 North Formosa Avenue, Los Angeles, in the county of Los Angeles, State of California, have invented a new, original, and ornamental Design for Tile, of which the following is a specification, reference being had to the accompanying drawing, forming part thereof.

The figure is a perspective view of a tile showing my new design.

I claim:

The ornamental design for tile substantially as shown.

EUGENE PARKER.
